Atty.

UNITED STATES PATENT OFFICE

RALPH R. SHAY, OF CHICAGO, ILLINOIS, ASSIGNOR, BY MESNE ASSIGNMENTS, TO
THOMAS A. BANNING, JR., OF CHICAGO, ILLINOIS

MOISTENER FOR GUMMED STRIPS AND THE LIKE

Application filed January 28, 1928, Serial No. 250,258. Renewed April 12, 1930.

This invention has to do with improvements in moisteners for gummed strips and the like. It has reference particularly to improvements in moisteners for moistening the gummed strips delivered from gummed strip feeding machines such as are used, among other things, for delivering strips of gummed paper for sealing packages and the like.

10 The moistener herein disclosed is adapted to moisten the gummed surface of the strip at a position immediately beyond the cutting blades by which the strip is severed from the reel; but it will also appear that features of the present invention may be used in connection with moisteners for other locations.

One of the objects of the invention is to provide a moistener as a unit capable of 20 ready attachment to other portions of the machine.

Another object of the invention is to provide a moistener having a wick by means of which the moisture is carried up from the 25 bath and is delivered to a capillary surface over which the gummed surface of the strip is drawn. This wick and this capillary surface are formed as a single element so as to more effectively deliver the moisture to the 30 desired point; and, further, these parts are so arranged that they may be adjusted from time to time in order to present fresh surfaces to the moistening position in order to compensate for wear and the like.

Another object of the invention is to provide a chamber for the water bath, which chamber is so constructed that it may be readily removed from or set back into place within the machine and without having to 40 perform special adjustments or manipulations to accomplish this result. In this connection, the chamber element itself is so constructed that when set into place it will naturally assume a very advantageous and satisfactory operating position without special adjustment.

Another feature of the invention relates to the provision of an improved flexibly supported bearing or pressure element for insuring the proper amount of contact of the

tape with the wick surface. This element itself is so constructed that it may undergo a considerable amount of freedom of movement, especially in a vertical direction, but is so arranged that it will naturally lie on 55 the tape strip in a manner to give the desired amount of pressure at all times.

In connection with the foregoing, it is a further object to provide spring means for drawing the pressure element into place 60 against the strip, said spring means being also of a very simple construction and so arranged as to take care of the desired amount of freedom of movement.

Other objects and uses of the invention 65 will appear from a detailed description of the same, which consists in the features of construction and combinations of parts hereinafter described and claimed.

In the drawings, — 70

Fig. 1 shows a longitudinal section through the delivery end portion of a paper strip feeding machine having applied thereto a moistening device embodying the features of the present invention; Fig. 1 may 75 also be considered as a section on the line 1—1 of Fig. 3, looking in the direction of the arrows;

Fig. 2 is a cross section on the line 2—2 of Fig. 1, looking in the direction of the 80 arrows;

Fig. 3 is a plan view corresponding to Figs. 1 and 2;

Fig. 4 shows a cross section on the line 4—4 of Fig. 1, looking in the direction of 85 the arrows;

Fig. 5 shows a perspective view of the wick and pressure plate element, a portion of the pressure plate being broken away to better illustrate the manner in which the wick 90 itself is supported; and

Fig. 6 shows a plan view corresponding to Fig. 5, but with the pressure plate entirely removed or cut away.

The front portion of the paper strip feeding machine is designated in its entirety by the numeral 7. It has side plates 8 and 9 and a floor or base section 10, which together establish between them a channel-shaped chamber in the front portion of the 100

machine. The front end of this chamber is open except for the presence of the moistening device and bath presently to be explained. The base member 10 is suitably supported, as by means of pedestal blocks 11.

5 The paper strip is fed downwardly through suitable guide chutes 12 and is delivered past the fixed and movable cutting blades 13 and 14, respectively, when said blades are separated by the proper actuating mechanism. The blade 14 is pivoted at the point 15 (see Fig. 3) and a spring 16 may be provided for drawing the blades together under the desired amount of shearing contact.

10 After the blades have been separated the paper strip is advanced by the feeding mechanism and it passes across the upper portion of the channel opening already referred to.

15 The moistening device includes a sheet-metal plate 17 of relatively thin but sufficiently stiff sheet-metal. The central portion 18 of this plate is formed downwardly, as best shown in Fig. 5, leaving the side flanges 19 and 20, which are adapted to rest upon the upper edge flanges 21 and 22 of the side plates 8 and 9 already referred to. These flanges 19 and 20 may be secured to the flanges 21 and 22 by means of screws 23 and 24 (see Fig. 3). Said screws are accommodated in slotted openings 25 and 26 of the flanges 19 and 20, and in order to facilitate adjustment and removal operations 20 said slotted openings may be enlarged at one end, as shown in Figs. 5 and 6. With this arrangement the screws 23 and 24 may be loosened up slightly and then the moistening device may be slipped backwardly a short 25 distance, whereupon it may be lifted bodily away from the frame of the machine.

20 The plate 17 is provided near its front edge with a relatively narrow slot 27, and near its rear edge it is provided with another slot 28. The latter slot is more or less covered over and protected by a lip 29, which is established by forming the metal of the plate 17 upwardly and curving it, as best shown in Figs. 1, 5 and 6. Likewise, the front edge of the slotted opening 28 is more or less protected by a tongue 30, which is established by forming the metal down slightly, as shown in Fig. 1.

25 The foregoing openings 27 and 28 are for the accommodation of a capillary wick 31. Said wick is made of any suitable material, such as compacted felt, and is of a width slightly less than the width of the openings 27 and 28. The thickness of this wick is 30 preferably approximately the same as or slightly greater than the amount of offset at the position 18 so that the top surface of the wick lying across said plate 18 will be advantageously presented to the advancing 35 gummed strip.

The wick is fed through the two openings 27 and 28, and between the tongues 29 and 30. The ends of the wick 32 and 33 are allowed to depend down into the water bath, and preferably the depending portions of the wick are loosely clipped together, as by a sheet-metal clip 34. This clip is preferably rather loosely placed on the wick so as not to seriously interfere with its capillary function, and also to allow the wick to be adjusted from time to time.

35 There is a pressure plate 35 located above the plate 17 and overlying the tape as it advances across the wick. This pressure plate 35 is preferably connected to the rear portion of the plate 17 by a pair of pins 36 and 37. The holes in the plate 17 are made large enough, as shown in Fig. 6, to allow the necessary freedom of movement of these pins so as to allow the pressure plate 35 to be 40 raised a considerable amount, as shown by the dotted lines in Fig. 1. The pressure plate normally lies in the full-line position of Fig. 1, so that the paper strip will be firmly held against the wick.

45 There is a light spring 38 of strip spring metal placed between the bottom face of the plate 17 and the heads 39 and 40 on the lower ends of the pins 36 and 37, respectively. The central portion of this bow spring is turned upwardly, as shown in Fig. 4, and presses against the bottom face of the plate 17, thus tending to pull down on the pins 36 and 37. The amount of this downward pull is sufficient to assist in holding the pressure plate 50 down in the lowered position, and at the same time will allow said plate to adjust itself freely as needed. Preferably the rear edge of the plate 17 is turned downwardly, as shown at 41 in Fig. 1, so as to assist in guiding the paper strip between the plate 17 and the pressure plate 35.

55 The water bath is established by means of a cup 42. Said cup includes a front plate 43, the width of which is sufficient to overlie the front ends of the side plates 8 and 9 (see Figs. 2 and 3). This cup 42 is also provided with the lugs 44 and 45 which set down into companion sockets in the base 10. The bath naturally tends to tilt backwardly due to the fact that it is supported in an off center position, and it therefore rests with the edges of its front plate 43 supported against the front ends of the side plates 8 and 9.

60 The bath proper is established by means of the sides 46 and 47, the back 48 and the bottom 49, the top of the bath being left open. Preferably also the upper front edge 50 of the bath is cut away slightly so as to establish an ample clearance at the point where 65 the moistened tape is delivered.

65 It will be understood that the bath may be readily lifted away from the remaining portions of the machine so as to either replace the water or for other purposes, such opera- 70

tion being permitted by the amount of clearance established at the upper end of the bath chamber. This operation is also facilitated by the fact that the depending portions of the wick are very flexible and will allow the same to be deflected forwards when the bath is inserted or removed.

In order to facilitate manipulation of the screws 23 and 24, the pressure plate 35 may be provided with openings 51 and 52 in line with the openings 25 and 26 already referred to, said openings 51 and 52 being of proper size to allow the screws heads to be passed through them.

While I have herein shown and described only a single embodiment of the features of my present invention, still I do not intend to limit myself thereto except as I may do so in the claims.

I claim:

1. In a device of the class described, the combination of a water bath comprising a rectangular chamber open at its top and having a slanting front wall, and a paper guide and presser element above said chamber, the same comprising a plate having its central portion depressed downwardly to establish an upwardly facing channel, and having a transversely extending slot across the front portion of said channeled portion, and also having a transversely extending slot across the rear portion of said channeled portion, an upwardly and forwardly facing flange on the channeled portion reaching forwardly above the rear slot aforesaid, a downwardly and forwardly facing flange on the channeled portion reaching rearwardly below the rear slot aforesaid, a capillary wick comprising a strip of capillary material threaded through the two slots of the channeled portion and lying across the top face of said channeled portion between the slots thereof, and having its ends depending into the water bath, and a presser plate above the channeled plate and wick, said presser plate having a pair of pins loosely extending through the rear portion of the channeled plate, together with a spring between said pins and the bottom face of the channeled plate tending to draw the presser plate down into contact with the wick where it passes across the top face of the channeled plate, substantially as described.

2. In a device of the class described, the combination of a water bath comprising a chamber open at its top, and a paper guide and presser element above said chamber, the same comprising a plate having its central portion depressed downwardly to establish an upwardly facing channel, and having transversely extending slots across the front and rear portions of the channeled portion aforesaid, an upwardly and forwardly facing flange on the channeled portion reaching forwardly above the rear slot, a down-

wardly and rearwardly extending flange on the channeled portion reaching rearwardly below the rear channel slot, a capillary wick comprising a strip of capillary material threaded through the two slots of the channeled portion and having its ends depending below the paper guide and presser element into the water bath, and a presser plate above the channeled plate and wick, said presser plate having a pair of pins loosely extending through the rear portion of the channeled plate, together with a spring between said pins and the bottom face of the channeled plate tending to draw the presser plate down towards the wick where it passes across the top face of the channeled plate, substantially as described.

3. In a device of the class described, the combination of a water bath open at its top, and a paper guide and presser plate element above said water bath, the same comprising a plate having its central portion depressed downwardly to establish an upwardly facing channel, and having a pair of transversely extending slots across the front and rear portions of the channeled portion aforesaid, a capillary wick comprising a strip of capillary material threaded through the two slots of the channeled portion and lying across the top face of said channeled portion between the slots thereof, and having its ends depending into the water bath, and a presser plate above the channeled plate and wick, and having its rear end loosely connected to the rear portion of the channeled plate, and having its body portion lying on the wick at the point where it passes across the top face of the channeled plate, substantially as described.

4. In a device of the class described, the combination of a water bath open at its top, and a paper guide and presser plate element above said water bath, the same comprising a lower plate having transversely extending slots across its front and rear portions, a capillary wick extending through said slots and lying across the top face of the plate and having its ends depending into the water bath, together with a presser plate above the wick and the first mentioned plate, and having its rear portion loosely connected to the rear portion of the first mentioned plate, substantially as described.

RALPH R. SHAY.
